CLAIM

I claim the ornamental design for an adjustable-length bungee strap, as shown and described.

DESCRIPTION

FIG. 1 is a perspective view of an adjustable-length bungee strap showing my new design;

FIG. 2 is an end elevational view thereof;

FIG. 3 is an opposite end elevational view thereof;

FIG. 4 is a side elevational view thereof, the opposite side elevational view being a mirror image thereof;

FIG. 5 is a top plan view thereof;

FIG. 6 is a bottom plan view thereof; and,

FIG. 7 is a reduced perspective view showing the adjustable-length bungee strap in use; the broken lines showing environmental structure are for illustrative purposes only and form no part of the claimed design.

The elements of the claimed design are shown detached for clarity of illustration.
